Primary Examiner — L. A. Grabenstetter*Assistant Examiner* — Danielle Nichole Bowly(74) *Attorney, Agent, or Firm* — McGinn IP Law Group, PLLC(57) **CLAIM**

The ornamental design for a tray for paper output, as shown and described.

DESCRIPTION

FIG. 1 is a front view of a tray for paper output showing our new design;

FIG. 2 is a rear view of the tray for paper output;

FIG. 3 is a top view of the tray for paper output;

FIG. 4 is a bottom view of the tray for paper output;

FIG. 5 is a right view of the tray for paper output;

FIG. 6 is a left view of the tray for paper output; and,

FIG. 7 is a perspective view of the tray for paper output.

The broken lines shown in the drawings represent portions of the digital multifunction device that form no part of the claimed design.

1 Claim, 7 Drawing Sheets(56)
